ATTORNEY

UNITED STATES PATENT OFFICE

FRED C. FANTZ, OF WEBSTER GROVES, MISSOURI

RETURN BEND FITTINGS FOR OIL STILLS

Original application filed December 8, 1931, Serial No. 579,707. Divided and this application filed February 3, 1932. Serial No. 590,628.

My invention relates to that class of return bends such as are described in my copending application, Serial No. 579,707, filed December 8, 1931, of which this application is a

10 division. As described in that application, the housing for the return bend proper is sectional comprising four parts, two for each tube. The tubes are generally mounted in nests or banks and the adjacent ones are connected to the return bend and in communication therewith. Outwardly projecting shoulders are formed on the tubes adjacent the ends thereof, and the housing sections are provided 15 with arcuate flanges which contact the shoulders on the tubes. Means are mounted in the housing sections which are adapted to draw the flanges upwardly and in turn the tubes and at the same time to press the return bend 20 downwardly against the ends of the tubes thus forming a tight joint.

My invention has for its object to provide improved means for holding the housing sections together and for a further object to 25 accomplish that result without requiring wide centers for the tubes in the nest or bank.

My means of accomplishing the foregoing objects may be more readily understood by having reference to the accompanying drawing, which is hereunto annexed and made a 30 part hereof, in which—

Fig. 1 is a side elevation of a return bend employing my improvement, a part of the wall being broken away to show the joint between the tube and return bend;

Fig. 2 is a vertical sectional view through one of the tubes, return bend proper and the housing sections; and

Fig. 3 is a plan view of means for securing 40 the housing sections together.

Similar reference numerals refer to similar parts throughout the entire description.

As shown in the drawing, the housing comprises pairs of complementary sections 1 and 2, and 3 and 4. Though I have shown the compound housing made up of four sections it can well be made, if found desirable, in practice, in halves, the sections 1—3 and 2—4 being cast or forged together. The return bend 5 is mounted in the housings and is

preferably provided with V shaped grooves 6 in its faces 7. These grooves 6 are adapted to receive the ends 8 of the tubes 9 and 10 which are preferably convex in section to furnish a line contact with the V shaped grooves 55 6. Although I have shown a specific form of joint which I prefer for the splendid results secured in practice with one joint of this type, I do not desire to be understood as limiting myself thereto as many forms of 60 joint may be employed in this device. On the tubes 9 and 10—inasmuch as the constructions are identical I shall describe only one—I form a shoulder 11, which is engaged by shoulders 12 and 13 formed on sections 1—3 65 and 2—4 respectively. These sections have upwardly extending side walls, in which may be mounted set screws 14, the inner ends of which are adapted to contact abutments 15 and 16 formed on the external wall of the 70 return bend 5, the center being in line with the center of the tubes. The lower portions of the housing sections are each provided with integral extensions 17 which partially encircle the tubes. The outer surfaces 18 75 of these extensions are tapered. To these tapered surfaces 18 I fit a ring 19, the inner walls of which are correspondingly tapered so that when in place the housing sections 1 and 2, and 3 and 4 are held firmly together, 80 this causes the shoulders 12 and 13 on the sections to interlock therewith so that by tightening the set screws 14 the tubes will be drawn tightly against the return bend 5 forming a tight joint. Although I have shown 85 a ring 19 on each pair of extensions 17 it will be clear to persons skilled in the art that they may be connected as by a web or plate 20 in the manner shown in the detail view Fig. 3. If desired, suitable means may 90 be used to hold the plate up such as by bolts or screws, but I prefer the tapered surfaces for that purpose. As illustrated I have shown the mounting means for the set screws 14 as consisting of a boss 21 formed on the 95 section 1 provided with internal threads in which is mounted the set screw 14. The complementary section 2 is provided with a laterally extending portion 22 which has an aperture 23 formed therein which is fitted 100

to the exterior wall of the boss 21 but I wish it to be clearly understood that any of the well known mountings employed for this purpose in devices of this kind may be employed without deviating from my invention. 5 From the foregoing description and an inspection of the drawing, it will be apparent that the return bend 5 may be quickly and conveniently removed, as it is very easy to loosen the set screws 14 and by removing the rings 19 or plate 20 the sections may be removed affording access to the return bend for removal which permits the removal or inspection of the tubes as desired.

10 15 Having described my invention what I regard as new and desire to secure by Letters Patent, is:

1. In a refinery apparatus, a return bend, a pair of shouldered tubes communicating therewith, a compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, securing means to contact said extensions and hold said sections together, the outer surface of 20 25 30 35 40 45 50 said extensions tapering downwardly and inwardly, said securing means having tapered apertures which fit said extensions whereby said sections are held together.

2. In a refinery apparatus, a return bend, a pair of shouldered tubes communicating therewith, a compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, securing means to contact said extensions and hold 45 50 55 60 65 70 75 80 85 90 95 100 105 110 115 said sections together, the outer surface of said extensions tapering downwardly and inwardly, said securing means having tapered apertures which fit said extensions whereby said sections are held together, and means to hold said securing means in place.

3. In a refinery apparatus, a return bend, a pair of shouldered tubes communicating therewith, a four-part compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, securing means to contact said extensions and hold said sections together, the outer surface of said extensions tapering downwardly and inwardly, said securing 65 70 75 80 85 90 95 100 105 110 115 means having tapered apertures which fit

said extensions whereby said sections are held together, and means to hold said securing means in place.

4. In a refinery apparatus, a return bend, a pair of shouldered tubes, communicating therewith, a compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, a pair of rings to contact said extensions and hold said sections together, the outer surface of 70 75 80 85 90 95 100 105 110 115 said extensions tapering downwardly and inwardly said rings having tapered apertures which fit said extensions whereby said sections are held together.

5. In a refinery apparatus, a return bend, a pair of shouldered tubes communicating therewith, a compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, a plate having apertures therein adapted to contact said extensions and hold said sections together, the outer surface of said extensions tapering downwardly and inwardly, to fit the aperture in said plate.

6. In a refinery apparatus, a return bend, a pair of shouldered tubes, communicating therewith, a four-part compound housing therefor, comprising complementary sections adapted to partially encircle the ends of said tubes and to be locked to the shoulders on the tubes, detachable means mounted in said housing sections to hold said tubes and return bend in a tight joint, extensions on said housing sections which contact said tubes, a plate having apertures therein adapted to contact said extensions and hold said sections together, the outer surface of said extensions tapering downwardly and inwardly, to fit the aperture in said plate, and means to hold said securing means in place.

In witness whereof, I hereunto set my hand.

FRED C. FANTZ.
